GARMENT HANGER

Robert Honig, 641 W. 169th St., Manhattan City, N.Y.
Filed Jan. 30, 1959, Ser. No. 790,137
1 Claim. (Cl. 223—95)

This invention relates generally to garment hanging devices, and is especially concerned with novel improvements in garment hangers of the type adapted for hanging pants, skirts and the like.

As is well known, it is desirable in the hanging of certain types of garments, such as pants and skirts to simultaneously suspend and stretch the garment, thereby preventing improper creasing thereof. Toward this end certain prior hanger constructions have been proposed, but have not found general acceptance for numerous reasons, particularly their relative complexity in construction and expense to manufacture. Further, prior devices of this general type have been too readily subject to breakage and malfunctioning by reason of their structural deficiencies and difficult operational procedures.

Accordingly, it is an object of the present invention to provide a garment hanger of the type described which overcomes the above mentioned difficulties, is extremely simple in construction and durable in use, capable of successful operation with little or no skill, and which is well adapted to be mass produced at a reasonable cost.

Other objects of the present invention will become apparent upon reading the following specification and referring to the accompanying drawings, which form a material part of this disclosure.

The invention accordingly consists in the features of construction, combinations of elements, and arrangements of parts, which will be exemplified in the construction hereinafter described, and of which the scope will be indicated by the appended claim.

In the drawings:

FIG. 1 is a front elevational view showing a garment hanger constructed in accordance with the teachings of the present invention, with parts shown in dot-and-dash outline in an alternative position of use;

FIG. 2 is a sectional view taken substantially along the line 2—2 of FIG. 1, somewhat enlarged for clarity of detail;

FIG. 3 is a sectional view, also enlarged, taken substantially along the line 3—3 of FIG. 1;

FIG. 4 is a sectional view taken substantially along the line 4—4 of FIG. 1; and

FIG. 5 is a perspective view of a second embodiment of the invention.

Referring now more particularly to the drawings, and specifically to FIG. 1 thereof, a garment hanger is there illustrated and is generally designated 10. The hanger may include a suspension member 11, a coat or blouse supporting member 12, and a pants or skirt supporting mechanism 13. The suspension element may be formed of wire or rod stock and bent to define a hook 15 and a generally vertically depending stem 16.

The coat or blouse supporting member 12 may be disposed to extend generally laterally or horizontally, being of an upwardly bowed configuration and receiving the stem 16 vertically through a medial region of the member 12. The stem 16 may be flattened or swaged to define enlargements 17 and 18, respectively above and below the blouse supporting member 12 to locate the latter in position on the stem.

The pants or skirt supporting mechanism 13 includes a laterally or generally horizontally extending elongated frame member or rod 20 having its medial region fixed by any suitable means to the lower end of the stem 16, so as to extend generally longitudinally of and beneath the blouse supporting member 12. However, the frame

2

member or rod 20 terminates at its opposite ends short of opposite ends of the member 12, and is there formed with rigidly depending guide members or loops 21. That is, the guide members 21 may be formed integral with the frame members 20, being bent, as best seen in FIG. 2, to define the looped configuration lying in planes parallel to each other and transverse or normal to the longitudinal extent of the frame member 20.

Adjacent to each end region of the frame member 20, 10 extending longitudinally of the frame member and in substantial alinement with each other, are a pair of elongate rods or extension members each being designated 22. Each extension member or rod 22 is slidably received or extends loosely through a respective depending loop 21 for sliding reception therein. The inner end of each extension member 22, inward of the adjacent guide loop 21, is bent to define a rigidly upstanding loop 23 located in a plane normal to the respective extension member and loosely circumscribed about or slidably receiving the adjacent region of the frame member 20. Thus, being constrained by the loops 21 and 23, each extension member 22 is longitudinally slideable relative to the frame member 20 for an extensible and retractile movement of the outer end relative to the frame member.

25 On the inner end of each extension member 22, formed integrally therewith or fixedly secured thereto by any suitable means, is a rigidly depending anchoring element 25, which may assume the form of a loop, as illustrated in the drawings, located in a plane disposed longitudinally of the respective extension member. Extending longitudinally of and along the underside of the inner region of each extension member 22, between the receiving guide loop 21 and the inner end anchoring element 25 is a coil extension spring 26. Each of the springs 26 has its opposite ends respectively connected to the adjacent loop 21 and anchoring element 25, as by end loops 27 and 28 of the spring. Thus, each of the extension members 22 is supported for its longitudinally extensible and retractile movement as described hereinbefore, and resiliently urged toward a fully extended condition by contraction of the spring 26. The extensible members 22 are limited to an extended condition, as indicated in solid lines in FIG. 1, by interposition of the springs 26 between the loops 21 and 25 to prevent further movement of the loops toward each other, and the extension members are retractile to the dot-and-dash outline positions by expansion of the springs 26.

On the outer end of each extension member 22 is provided a depending garment engaging element 30, which 50 may consist of a downwardly bent extension 31 of the extension member 22, preferably sheathed or covered by a tubular element 32 of soft, frictional material, such as rubber, plastic or the like. Thus, the garment engaging elements 30 are movable inward to the phantom position in FIG. 1, and resiliently urged outward for engagement in a garment to support the same suspended therefrom. That is, the sheathed garment engaging element 30 may be engaged in the waist of a skirt or pants, or in the legs thereof and allowed to resiliently extend into frictional retaining engagement with the receiving garment.

If it is desired, the hanger 10 may be provided with a pair of pants or skirt holding mechanisms, say one for each pants leg, or the extension members 22 may each be provided on their outer ends with a pair of garment engaging elements corresponding to those designated 30.

FIG. 5 shows an embodiment wherein hanger 40 is provided with a pair of pants holding mechanisms 46 and 46a. Hook 43 has a depending stem 45 which extends through coat supporting member 44, similarly to the first embodiment. A pair of stem extensions or rods 42 and 41 are fixed to the bottom end of stem 45 by any suitable means (not shown) and are respectively inclined

forwardly and rearwardly downwardly therefrom. The lower end of rod 42 is fixed by any suitable means (not shown) to the center of rod 48 of front mechanism 46. The lower end of rod 41 is fixed by any suitable means (not shown) to the center of rod 47 of rear mechanism 46a.

Rods 48 and 47 are parallel to each other and in front-to-rear registration with each other, and are generally parallel to member 44. The mechanisms 46 and 46a are otherwise the same as mechanism 13, as is clearly shown in the drawing, and the same reference numerals are used to indicate corresponding parts thereof.

From the foregoing, it is seen that the present invention provides a garment hanger which fully accomplishes its intended objects and is well adapted to meet practical conditions of manufacture and use.

Although the present invention has been described in some detail by way of illustration and example for purposes of clarity of understanding, it is understood that certain changes and modifications may be made within the spirit of the invention and scope of the appended claim.

What is claimed is:

A garment hanger comprising an elongate normally horizontal rod adapted to be suspended from a support, a guide loop rigidly depending from each end of said rod and each located in a plane generally normal to the rod, a pair of elongate extension members each arranged longitudinally of and adjacent to a respective end of said rod and having an intermediate region extending slidably

through the adjacent guide loop, an additional guide loop on the end of each extension member inward of said first mentioned guide loops upstanding rigidly from the respective extension member in a plane generally normal to the latter and slidably receiving the adjacent portion of said rod, depending garment engaging elements on the outer ends of said extension members outward of said first mentioned guide loops, an anchoring element depending from the inner end of each of said extension members, and a pair of coil springs each extending along the underside of a respective extension member and having its opposite ends connected to the first mentioned guide loop of the respective extension member and the anchoring element thereof, to resiliently urge said extension members toward their extensible condition.
